UNITED STATES PATENT OFFICE.

KENNEDY PARK, OF TOLEDO, OHIO, ASSIGNOR TO THE TOLEDO BOILER WORKS COMPANY, OF TOLEDO, OHIO, A CORPORATION OF OHIO.

WATER-TUBE BOILER.

No. 855,661.

Specification of Letters Patent.

Patented June 4, 1907.

Application filed December 3, 1906. Serial No. 346,025.

To all whom it may concern:

Be it known that I, KENNEDY PARK, a citizen of the United States, and a resident of Toledo, in the county of Lucas and State of Ohio, have invented certain new and useful improvements in Water-Tube Boilers; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to boilers for the generation of steam, and particularly to the water-tube type of boilers in which the water-tubes are connected at their ends to headers or manifolds which stand substantially in vertical planes.

An object of the invention is to so mount the headers or manifolds relative to the framework of the boiler as to facilitate the ready and easy removal or mounting of any or all of said headers and also to permit a free movement of each header or manifold as the water-tubes contract or expand, thus preventing a distortion of the tubes due to the expansion thereof and consequently prolonging their lives.

A further object of the invention is to so construct and apply the hand-hole caps of the headers as to make a stronger and better joint between the header and cap, as is hereinafter more fully described.

The invention is fully described in the following specification and illustrated in the accompanying drawings, in which,—

Figure 1 is a vertical longitudinal section of a steam-generator embodying the features of my invention. Fig. 2 is a front elevation thereof with a portion of the casing removed and the exposed headers shown as devoid of their hand-hole caps. Fig. 3 is a longitudinal section of one of the headers with the tubes and hand-hole caps secured thereto. Figs. 4 and 5 are rear and front elevations, respectively, of a header with the tubes and caps removed. Fig. 6 is an enlarged central section of a hand-hole cap and retaining spider attached to the header casing, and Fig. 7 is a similar view of the same illustrating the co-operating action of the header with the

header casing when a bowing stress is applied to the former by a tightening of the bolt. 55

Referring to the drawings, 1 designates the front of a steam-generator of ordinary construction, 2 the water-tubes thereof, which connect fore and aft with the usual headers or manifolds 3 and 4, respectively, and 5 transverse centrally-disposed steam and water drums, which connect with the headers through the banks of tubes 6. The headers or manifolds 3—4 are shown in the drawings as being of sinuous formation, but may be of any other desired shape or size, and as having their hand-holes 7 closed by the usual caps 8, which are held to their seats by the co-operation therewith of the spiders 8^a and bolts 8^b.

Surmounting the forward end of the boiler frame and supported both by the brick work and the standards 9, to which latter it is riveted or otherwise suitably secured, is the transverse girder 10, which is shown as comprising the two spaced channel bars 11—11 and the superimposed spanning plate 12, which latter rests upon said bars, thus forming a light but rigid girder of inverted U-shaped construction. I wish it understood, however, that I do not confine myself to such construction of girder or its manner of mounting, as the construction of the same may be changed as desired.

The several forward headers 3 of the boiler are intended to be supported by the girder 10 in pendent relation thereto through the medium of the rods or suspending members 13, each of which is shown in Fig. 1 of the drawings as having its upper end passed through a slightly enlarged aperture in the girder-plate 12 and prevented from withdrawal therefrom by a nut or head 14, and its lower end pivotally secured in any suitable manner to a perforated lug or ear 15 on the upper end of the associated header 3, whereby a free swinging movement of each header is permitted.

With the method heretofore employed of rigidly mounting both sets of headers, no movement thereof was permitted to allow for a longitudinal contraction and expansion of the water-tubes, thus causing them to become bent and distorted, due to the expanding stress, and liable to breakage when cooling and returning to their normal contracted state. It is apparent, however, with my im-

proved method of mounting the headers 3 that each header is permitted to have a free swinging movement relative to its supporting means to allow for the lengthening or shortening of the tubes as they expand or contract, and that a bending or distorting of the tubes and evils resulting therefrom is obviated. The rear headers 4 are shown as being rigidly mounted in the usual or any convenient manner, as it is only necessary to mount the headers at one end of the boiler for movement relative to the supporting parts. It is also apparent that this manner of mounting the headers 3 enables any or all to be easily and quickly disconnected from the supporting means and removed from the boiler for the purpose of repair or substitution.

Having thus described my invention, what I claim as new and desire to secure by Letters Patent, is,—

1. A water-tube boiler having pendent swingingly mounted headers or manifolds for the tubes, which are free from a subjacent support.
2. The combination with the several headers at one end of a water-tube boiler, of superimposed means supporting the several headers for relative swinging movements, said means serving as the sole support for the headers.
3. A water-tube boiler having pendent swingingly mounted headers or manifolds for the tubes, and rigid means from which the headers or manifolds are suspended.
4. The combination in a water-tube boiler, of the water-tubes, fore and aft sets of head-

ers to which the ends of the tubes are connected, a girder superimposing one set of headers, and means for swingingly suspending the several headers of said set from the girder, said means being the sole support for the headers.

5. The combination with the forward headers of a water-tube boiler, of a girder rigidly mounted above said headers, and suspender members coöperating with the girder and headers to maintain the latter in movable suspended position, said members being the sole means of support for the headers.

6. The combination with the several headers at one end of a water-tube-boiler, of a superimposed girder, and a plurality of members suspended from the girder and each swingingly carrying different ones of said headers to permit them to have independent swinging movements.

7. The combination with the boiler tubes, of a plurality of independent headers at the forward ends of the tubes, a girder superimposing the headers, means swingingly suspending the headers from the girder for independent movements, a transverse drum superimposing the tubes at the rear of the girder, and tubes connecting the headers and drum.

In testimony whereof I have hereunto signed my name to this specification in the presence of two subscribing witnesses.

KENNEDY PARK.
